UNITED STATES PATENT OFFICE.

FREDERICK WALTHER, OF OMAHA, NEBRASKA.

CRATE.

Application filed August 3, 1923. Serial No. 655,494.

To all whom it may concern:

Be it known that I, FREDERICK WALTHER, a citizen of the United States, residing at Omaha, in the county of Douglas and State 5 of Nebraska, have invented new and useful Improvements in Crates, of which the following is a specification.

My present invention pertains to poultry crates and the like and it contemplates the 10 provision of an inexpensive crate that is light and durable in construction and at the same time is adapted to be collapsed into a small area.

The invention further contemplates the 15 provision of a crate that may be shipped to a distant point and then returned to the original point from which sent and this in a collapsed form.

The invention further contemplates the 20 provision of a collapsible crate that may, if desired, be employed for shipment of perishable goods in lieu of poultry and the like.

Further objects and characteristic advantages will readily be apparent from the following description and claims when the same 25 are read in connection with the drawings accompanying and forming part of this specification, in which—

Figure 1 is a perspective view of the crate 30 in its shipping position.

Figure 2 is a longitudinal sectional view of the crate.

Figure 3 is a transverse sectional view of the crate.

Figure 4 is a perspective view of the crate 35 collapsed.

Figure 5 is a view similar to Figure 2 but in collapsed position.

Figure 6 is a view similar to Figure 3 but 40 in collapsed position.

Similar numerals of reference designate corresponding parts in all the views of the drawings.

My novel crate comprises a base 1 that is 45 preferably solid and said base is provided with the upstanding edge 2. Hinged at 3 to end walls of the edge 2 are the end walls 4 that are provided with open panels and also hinged at 3 to the side walls of the edge 50 2 are side walls 5 of the crate. The walls 5 comprise two sections that are hinged at 6 as illustrated and hinged at 8 in the center of the base 1 is a partition wall 7 while secured to the base 1 adjacent the partition 7 55 9 as illustrated.

The upper wall or cover 11 is hinged at 3 to the upper end of the side walls 5 and said upper wall or cover 11 is provided with the depending edge 12 the end ones of which are 60 provided with openings 13 that are in registration with each other. The partition wall 7 is provided with a slot 16 that likewise registers with slots 13 of the ends 12 when the crate is open. A lock bar 14 is provided 65 to pass through the openings 13 and 16 and hold the crate in its non-collapsed state.

The end walls 4 are provided with the right angle portions 4^a and provided in the portions 4^a as well as the ends of bar 14 and 70 top of crate 11 are apertures that are in registration when the crate is set up and a pin 15 is adapted to enter the apertures and hold the end walls as well as the top in proper position with respect to the bar 14. 75

When in closed position as shown in Figure 5 the bar 14 seats through the opening 13 in the edge 12 of one side of top 11 and then through opening 9 of brace 10 and finally through opening 13 on opposite side 80 of edge 12 of the top. The bar 14 is locked in position by dropping pin 15 through apertures in the top of the cover 11 and into the aperture on the ends of bar 14.

To open the crate, the pins and bar are 85 removed and the side walls 5 pulled upwardly. The end walls are then extended to their upright position and the partition wall is likewise extended to its upright position.

The bar 14 is then passed so that it rests in the apertures 13 of edges 12 and also in aperture 16 of partition 7.

Manifestly the pins will lock the bar in position and hence the crate is locked in 95 open position.

The locking of the ends 13 of top 11 in open or closed position will likewise lock the ends 4 and sides 5 in similar positions.

The invention is extremely simple and 100 durable in construction and may be made of wood or metal as desired.

Should it be desired to ship vegetables or other articles, other than poultry, the panels of the sides, top and ends may be solid. 105

Having described my invention, what I claim and desire to secure by Letters-Patent is,

1. In a container, the combination of a base wall having an upturned flange, a wall 110 having an aperture and secured to the center of the base and a bracket having an aper-

ture and secured to the base adjacent the wall, side walls formed of two hinged sections that are hinged at one end to the base, a top having a flange in which slots are provided, and a bar having apertures therein and adapted to seat in the slots of the walls and bracket, substantially as and for the purpose set forth.

2. In a collapsible crate, the combination 10 of a base, end walls secured thereto and having an upper edge and also a slot therein, a partition wall hinged to the base and having a slot, a bracket secured to the base and having a slot, side walls formed of two sections 15 hinged to each other and to the base, a cover having a slotted flange and hinged to the sides, and a brace bar adapted to enter the slots of the cover, end and partition walls when the crate is open and further adapted 20 to enter the slots of the cover when the crate

is collapsed and pins for locking the bar to the walls.

3. In a collapsible crate, the combination of a base, a partition having an opening and secured to the base, a bracket secured to the base and having an aperture therein, side walls comprising two hinged sections, a top having a flange in which slots are provided, and a bar having apertures and adapted to seat in the openings of the partition and 25 bracket, substantially as and for the purpose set forth.

30 In testimony whereof I have hereunto set my hand in presence of two subscribing witnesses.

FREDERICK WALTHER.
